Attorney

UNITED STATES PATENT OFFICE

HARRY G. MILLER, OF DENVER, COLORADO

VALVE RESEATING TOOL

Application filed February 12, 1930. Serial No. 427,717.

This invention relates to improvements in pilots for use in connection with cutters for reseating valve seats in internal combustion engines.

5 It frequently becomes necessary to reseat the valve seats of internal combustion engines such as are employed in connection with automobiles and aeroplanes and for the purpose of obtaining the best results it is 10 necessary to employ a cutter that is guided by means of a pilot which is rigidly secured in the guide opening of the cylinder block.

The usual type of internal combustion engines is provided with guide openings which 15 are of the proper diameter to receive the valve stem, and with this type of engine, pilots like those shown and described in my copending application 310,354, filed October 20 4, 1928, are employed. Owing to the small diameter of the guide opening the pilots are rather flexible with the result that they do not hold the cutter firmly in concentric relation with the guide opening and unless a 25 special type of cutter is employed, it is very difficult, if not impossible, to get the valve seats concentric with the guide opening.

In at least one type of internal combustion engine now employed in connection 30 with automobiles, the guide openings are of much larger diameter than has heretofore been employed and are lined by means of two semicylindrical, removable bushings, which can be readily removed and which, 35 therefore leaves an opening of considerable diameter, for the reception of the lower end of the pilot.

Located directly beneath the guide openings are valve tappets that are axially 40 aligned with the openings and with the cylindrical valve port.

It is the object of this invention to produce a pilot that is specially designed for use in connection with engines of the above 45 mentioned construction and which, briefly described, consists of a cylindrical steel bar having a central portion of a diameter equal to the diameter of the guide opening and whose lower portion is cylindrical and of 50 slightly smaller diameter than the central

portion. A sleeve is slidably connected with the lower end of the pilot and the opening in the lower end of this sleeve is of the proper size to receive the upper end of the valve tappet. The upper end of the pilot is preferably, although not necessarily, of a smaller diameter than the central portion and is provided with an inwardly extending axial opening that is threaded for the reception of a screw. This screw can be rotated for the purpose of adjustment and serves as a stop for the cutter in a manner that will hereinafter appear. The lower end of the central portion is provided with a few turns of square threads that serve as cleaners for removing foreign matter from the guide opening when the pilot is inserted therein.

Having thus briefly described the invention, the same will now be described in detail and for this purpose reference will be had to the accompanying drawings in which the preferred embodiment has been illustrated and in which:

Fig. 1 is a vertical section taken through a valve port and its associated guide opening and which also shows the valve tappet and my improved pilot in place;

Fig. 2 is a section similar to that shown in Fig. 1 and shows a slightly modified form of cutter attached to the pilot;

Fig. 3 is a view partly in section and partly in elevation and shows a micrometer device attached to the screw for the purpose of rotating the latter through a predetermined angle;

Fig. 4 is a section taken on line 4—4, Fig. 3;

Fig. 5 is a section taken on line 5—5, Fig. 1;

Fig. 6 is a view looking in the direction of arrow 6, Fig. 2 and shows a bottom plan view of the roughing cutter;

Fig. 7 is a section taken on line 7—7, Fig. 6;

Fig. 8 is a section taken on line 8—8, Fig. 6, and shows the cutter employed for cutting the valve seat;

Fig. 9 is a section taken on line 9—9, Fig. 6 and shows the seventy-five degree cutter; and

Fig. 10 is a section taken on line 10—10, Fig. 6 and shows the manner in which the cutters are held in place.

In the drawings reference numeral 1 design-

nates a cylinder block of the type employed in connection with internal combustion engines. These blocks are provided with a plurality of valve ports 2 that are in axial alignment with 5 guide openings 3. Located directly beneath and axially aligned with the guide openings are valve tappets 4.

The upper ends of the valve ports are provided with inclined conical surfaces 5 that 10 form valve seats and these must be very accurately formed so as to be concentric with the guide openings and so as to have a predetermined angle and for the best results the valve seat must be absolutely concentric with the guide opening.

In the manufacture of the engine the valve ports, the guide openings and the openings in which the valve tappets are mounted, are usually formed by a single tool and are therefore concentric one with the other and in 20 perfect alignment.

After the engine has been in use for some time, the valve seats become worn or corroded and it becomes necessary to reseat the valves 25 and unless this is carefully done so as to make the valve seats concentric with the guide openings and so as to have them in a plane perpendicular to the axis of the guide opening, a good job cannot be had.

30 For the purpose of guiding the cutters so as to hold them in axial alignment with the openings, I have provided a pilot which I will now describe. This pilot is preferably constructed of steel and has a central cylindrical portion 6 that is of the same diameter as the openings 3 so that after the pilot has been inserted in place it will fit the opening so as to prevent any lateral movement of the pilot with respect to the engine block. The lower 40 end of the cylindrical surface 6 is preferably provided with a few turns of square threads 7. These threads serve as cleaners for the purpose of removing foreign matter from the inner surface of openings 3 when the pilot is 45 put into place. Beneath the central cylindrical section 6 the pilot is formed with a cylindrical surface 8 whose diameter is preferably equal to the root diameter of the threads 7. The lower end of section 8 is 50 adapted to rest on the upper end of a valve tappet in the manner shown in Fig. 1 and is provided with a sleeve 9 that has a sliding fit with the lower end of the pilot and the lower end of whose opening is of such size that it 55 will fit snugly the upper end of the valve tappet. Since the valve tappets are always of the same size and since the upper ends are not subjected to wear, the opening in sleeve 9 will always make a tight fit with the valve 60 tappet with which it is connected. Above the central section 6 the pilot is formed with a cylindrical section 10 that is usually of smaller diameter than the central section. The upper end of the pilot is provided with 65 an axial opening 11 that is threaded for the

reception of a screw 12. The opening and the screw are preferably provided with threads of one-fortieth of an inch pitch so that when the screw is rotated one-twenty-fifth of a turn, it will move longitudinally 70 one-thousandth of an inch. Section 10 is provided with a graduation mark 13 that extends parallel with the axis of the pilot and this in turn is provided with a plurality of transverse marks 14 spaced one-fortieth of an 75 inch apart. The upper surface of the head 15 of the screw is provided with a flat surface and has an opening 16 extending downwardly thereinto. For the purpose of rotating the screw I have provided a cap 17 that can be slipped over the screw and over the upper end of the pilot. This cap is provided with a pin 18 that extends into the opening 16 in the manner shown in Fig. 3. The lower end of the cap is provided with an inclined 80 surface 19 whose lower edge has a plurality of graduation marks 20. The circumference of the cap is divided into twenty-five equal spaces by the graduation marks and when the cap is rotated through an angle equal to the 85 distance between two adjacent marks, the screw will be moved one-thousandth of an inch in the direction of the length of the pilot. The purpose of this micrometer adjustment will be more fully explained as the 90 description proceeds. When the pilot is to be used it is put in place in the manner shown in Fig. 1 and will then be held in rigid alignment with the several openings. If desired a nut 21 can be applied to the threads 7 for the purpose of clamping the pilot in place, but this is not considered necessary and is usually dispensed with as the use of this nut consumes a considerable amount of time. After the pilot has been put into place, a 95 roughing cutter is applied to it in the manner shown in Fig. 2. For the best results this cutter must be constructed in the manner shown in Figs. 6 to 10, from which it will be 100 seen that it consists of a ring-like portion 22 that is provided with four radial openings x , y , y and z . The depth of these openings varies, that of opening x being greater than that of openings y and that of y being greater than that of opening z . Located in the opening x is a fly cutter 23, whose cutting edge 24 makes an angle of fifteen degrees with a plane perpendicular to the axis of rotation. Cutters 25 that are located in openings y have cutting edges 26 that make an angle of 45 degrees with the plane of rotation and cutter 27, that is located in opening z , has a cutting edge 28 that makes an angle of seventy-five degrees with the plane of rotation. These cutters are held in place by means of screws 29 for the reception of which threaded openings 30 have been provided adjacent each of the radial openings in the manner shown in Fig. 10. These screws are provided with heads having flat shoulders 31 that are adapt- 105 110 115 120 125 130

ed to engage the under surface of the cutters and hold them in place. Cutter 22 is secured to the lower end of a sleeve 33 and is held in position on this sleeve by friction. The upper end of the sleeve is closed by means of a threaded plug 36 which is adapted to engage the upper flat surface of head 15. Plug 35 is preferably provided with a 40 pitch thread and has a slot 32 that can be engaged by a screw driver. Lock nut 34 holds the plug in adjusted position. The upper section 37 of sleeve 33 is hexagonal and can be rotated by means of any special tool that is suitable for this purpose. This tool has not been shown as it does not form part of this invention. When the cutter is rotated the fly cutters will cut three surfaces which have been designated respectively as *a*, *b* and *c*. The surface *b* is the one with which the valve operates and is usually inclined at an angle of forty-five degrees. The depth of the cut is determined by the position of screw 15 and therefore if the valve tappet corresponding to the valve seat to be cut is always moved to its lower position before the pilot is put in place, the distance from the valve seat *b* to the tappet will always be exactly the same and it is therefore possible to so cut the valve seats that all of the valve stems can be made exactly of the same length. If for any purpose it is found desirable to cut one of the valve seats to a greater depth than the others, the exact difference can be determined by means of the micrometer attachment shown in Fig. 3 and the exact amount to be cut off from the corresponding valve stem can therefore be determined and in this way the fitting of the valves is greatly simplified. With the usual practice of fitting valve stems, the distance from the valve seats to the valve tappets is never the same as it is determined by chance and therefore each valve stem must be separately adjusted which requires a large amount of time and labor that can be almost entirely dispensed with when my valve reseating tool is employed.

After the roughing tool has been employed, a finishing cutter like that shown in Fig. 1 and designated by reference numeral 38 is used. This finishing cutter is of the ordinary construction and is secured to the tapered end 39 of a sleeve 40 that is substantially like that shown in Fig. 2. The depth to which this tool can cut is determined by the position of the screw 12 in the manner explained in connection with the roughing cutter or by the position of plug 35.

It is usually preferable to adjust the position of the finishing cutter by means of the plug 35 that can be rotated by means of a cap like that indicated by numeral 17 in Fig. 3 and by means of which the exact values of the adjustments can be determined.

To prevent accidental rotation of screw 12, the latter is split by two diametrical cuts and

spread so that it will press against the side of the opening and thereby produce sufficient friction to prevent it from rotating.

For inserting and removing the pilot applicant has provided a special tool that has not been shown and which is connected with the pilot by means of a bayonet slot.

From the above description it will be seen that I have produced a valve reseating tool that comprises a pilot of such construction that it can be made of fairly large diameter so that it will be comparatively rigid and which will be held in exact alignment with the guide opening and the valve tappet and therefore it enables the workmen to cut valve seats that are concentric with the axis of the guide openings. These pilots are provided with an adjustable screw that can be accurately positioned by means of a micrometer attachment and therefore, since the pilot rests on the upper end of the tappet, the distance between the valve seat and the tappet can always be accurately determined and if any change in this distance is made, the difference can be accurately measured and therefore the work of adjusting the valves is greatly reduced.

Having described the invention what is claimed as new is:

1. A pilot for use in reseating valve seats in engine blocks having valve seats concentric with guide openings, said pilot comprising a steel bar of circular cross section, the central portion of the bar having a cylindrical section of substantially the same diameter as the guide opening, the lower end of the pilot being so formed as to be supported on a valve tappet, a sleeve slidably connected with the lower end thereof, the upper end of the pilot having an axial threaded opening, a screw operatively associated with the opening and a cutter carrying sleeve connected with the upper end of the pilot, the cutter carrying sleeve having means near its upper end for engaging the upper end of the screw.

2. A pilot for use in reseating valve seats in engine blocks having valve seats concentric with guide openings, and valve tappets in alignment with the guide openings, said pilot comprising a steel bar of circular cross section, the central portion of the bar having a cylindrical section of substantially the same diameter as the guide opening, the lower end of the pilot being formed so as to be supported on the upper end of a valve tappet a sleeve slidably secured thereto, the opening in the lower end of the sleeve being of the proper size to receive the upper end of a valve tappet, the upper end of the pilot having an axial threaded opening, a screw operatively associated with the opening and means for adjusting the screw to any desired angle, said means comprising a cap having an opening adapted to receive

- the head of the screw and to receive the adjacent end of the pilot, the end of the cap being provided with equiangularly spaced graduations.
5. A device for use in reseating valve seats in cylinder blocks having valve seats axially aligned with guide openings and valve tappets located at the end of the guide openings opposite from the valve seats, said pilot having a central cylindrical portion of a diameter equal to the diameter of the guide opening, the lower end of the pilot being of less diameter than the central portion, the lower end of the central portion having a few turns of square threads, the pilot having its lower end formed so as to be supported on the upper end of a valve tappet a cylindrical sleeve slidably secured thereto, the lower end of the opening in the sleeve being of the same diameter as the valve tappet and adapted to receive the upper end of the latter, the upper end of the pilot having an axial opening adapted to receive an adjusting screw, and a screw in said opening.
4. A device for reseating valve seats in cylinder blocks having valve seats concentric with guide openings located between the valve seats and the valve tappets, comprising a pilot having a central cylindrical section of the same diameter as the guide opening and having its lower end so formed as to be supported on the upper end of a valve tappet, an adjusting screw secured in an opening in the other end of the pilot, a sleeve enclosing the screw and a portion of the pilot, a cutter secured to the sleeve and a bearing member located in the upper end of the sleeve and adapted to engage the end of the screw and to limit the downward movement of the sleeve and cutter.
5. A pilot for use in reseating valve seats in cylinder blocks having axially aligned valve tappets, guide openings valve seats and valve tappets below the guide openings, comprising a bar of circular cross-section, the central portion consisting of a cylindrical section whose diameter is equal to the diameter of the guide opening, the lower end consisting of a cylindrical section of diameter smaller than that of the central section and so formed as to be supported on a valve tappet, the lower end of the central section having a few turns of threads, a sleeve slidably connected with the lower end of the pilot the opening in the lower end of the sleeve being of sufficient size to receive the upper end of a valve tappet, the other end of the pilot having a threaded axial opening, and a screw rotatably secured in the opening.
6. In combination with a cylinder block having axially aligned valve seats, guide openings and valve tappets, a pilot consisting of a steel bar adapted to extend through the plane of the valve seat, through the guide

opening and to rest on the upper end of the corresponding valve tappet, the pilot having a central section of substantially the same diameter as the guide opening and having its lower end provided with a sleeve, the opening in the lower end of the sleeve being of sufficient size to receive the upper end of a valve tappet and adapted to make connection between the pilot and the upper end of the valve tappet.

In testimony whereof I affix my signature.
HARRY G. MILLER.
